UNITED STATES PATENT OFFICE.

LINCOLN MOSS, OF NEW YORK, N. Y.

HOISTING APPARATUS.

No. 863,203.

Specification of Letters Patent.

Patented Aug. 13, 1907.

Application filed February 4, 1904. Serial No. 191,928.

To all whom it may concern:

Be it known that I, LINCOLN MOSS, of New York, N. Y., (post-office address 62 Madison avenue, borough of Manhattan, city of New York,) have invented certain new and useful Improvements in Hoisting Apparatus, of which the following is a specification, illustrated by drawings.

This invention relates to hoisting apparatus of the class in which clam-shell or other buckets or carriers are employed and in which the carrier requires a motion of translation, as a hoisting motion, and also an internal motion or a motion of the parts of the carrier to close and open the carrier, the two motions being controlled by two or more ropes or chains or other power-transmitting devices.

The invention consists of certain features of construction and combinations of parts to be hereinafter described and then claimed, with reference to the accompanying drawings, which show the invention applied to a traveling bridge.

In the main the invention comprehends means for balancing the ropes, chains or other power-transmitting devices which are used for the purposes stated, so that there is no tendency for the carrier to move in either direction, and so that when the parts of the carrier are operated there is no tendency for the carrier to shift its position when power is applied for such operation.

Figure 1 is a perspective view partly diagrammatic, showing apparatus embodying the invention; Fig. 2 is a detail diagrammatic perspective view of the ropes.

Referring to the drawings, the bucket or carrier *a* is designed to deposit its load into a hopper *b*, which, together with the carrier, is supported on the frame-work of a bridge *c*, which is carried by trucks *d d'* that preferably travel on rails *e e'*. The bridge is provided with tracks or guide-rails *f* for the trolley or carriage *g* equipped with an electric motor *h*. The trolley or carriage *g* is provided with rollers *i*, one at least of which is driven from gears *j* connected with the motor *h*. The motor on the trolley is preferably supplied with current through wires, not shown, which are connected with a controller *y* that may be supported on a platform, as indicated by dotted lines, which platform may be used by the operator. The clam-shell or other bucket or carrier is supported by means of suspending ropes, chains or cables *k* which are attached to the head or bucket bail *a'* and the jaws or operating parts of the bucket or carrier are controlled through the medium of ropes, chains or cables *l* connected with the cylindrical surface of a drum *m*. The ropes *k l* are each in reality a doubled single rope, each rope being reeved through suitably arranged sheaves or pulleys, to be hereinafter described.

Pulleys *l' l'* suitably supported on the trolley or carriage *g* conduct the two ends or laps of the rope,

chain or cable *l* in opposite directions, one lap being reeved over the pulley *l'* at one end of the frame-work of the bridge and conducted past the trolley or carriage to the other end of the frame-work, where it is reeved over pulleys *l'* and is conducted in reversed direction over a pulley *l'*, thence the other lap or end of the rope, chain or cable is conducted over pulleys *l'* to the appropriate one of the aforesaid pulleys *l'*. The pulley *l'* serves as an equalizer for equalizing the stresses in either direction with respect to the trolley or carriage, no matter what may be the position of translation of the carriage with respect to the ends of the bridge. The manner of conducting the rope, chain or cable *l* balances the stresses in either direction with respect to the trolley or carriage *g*. No matter what may be the position of the latter, the rope *l* will have no effect in changing this position.

The rope, chain or cable *k*, which supports the bucket or other carrier and the ends of which are attached to a bail *a'*, is conducted, or rather, its two laps or ends are conducted in opposite directions over the pulleys *k' k'*, one lap or end being reeved over pulley *k'*, adjacent and preferably mounted on the same shaft, as the pulley *l'*, and being conducted past the trolley or carriage to and over pulleys *k'* at the opposite end of the bridge, whence the said lap or end is conducted to and over a pulley *k'*, which serves as an equalizer, the other lap or end of the rope, chain or cable being thence conducted over pulleys *k'*, whence it is conducted over the appropriate pulley *k'*.

A ram or hydraulic cylinder *n* is suitably supported on the frame-work of one end of the bridge in horizontal position, its plunger rod *n'* supporting the before-described equalizing pulley *l'*. Adjacent to and parallel with the ram or hydraulic cylinder *n* is a second ram or hydraulic cylinder *o*, the plunger rod *o'* of which supports the before-described equalizing pulley *k'*. These rams *n o* are operated by suitable fluid admitted to act on the plunger heads within them for the purpose of reciprocating the plunger rods and imparting corresponding movements to the equalizing pulleys carried by them. It is evident that when reciprocating movement is imparted to the plunger rod *n'* in one direction, it acts on the drum *m* to close the bucket or carrier, and when reciprocating movement is imparted in the other direction slack on the rope *l* occurs, thus permitting the parts of the carrier to open by gravity. Similarly, the rope *k* is operated for the purpose of raising or lowering the bucket or carrier so that, whether the bucket be in one or the other elevated position, or whether the parts thereof be opened or closed in any position, the stresses will be balanced.

For the purpose of supplying a substantially constant maximum hydraulic pressure for operating the cylinders or rams without necessitating a continual stopping and starting of the motive power, I prefer to em-

ploy a constantly running motor, such for instance, as an electric motor p , which is provided with a controller p' and a master switch p^2 for the controller, a centrifugal pump q being employed to be actuated by the motor. Thus the pressure produced by the pump, disregarding frictional resistance, will be almost constant within the working limits of the apparatus and the system will be self-regulating to the extent that the pump and motor can operate continu-
 10 ously, even though no water is flowing through the pump. The tank r supplies water through a pipe q' to the pump, while a discharge pipe q^2 conducts water to an accumulator s containing some air or fluid and which is preferably employed to prevent shocks on the apparatus. The accumulator s is preferably connected by means of a pipe s' with a pressure-actuated regulator s^2 for the motor controller p' for evident reasons. From the accumulator s the main supply pipe t for the rams or hydraulic cylinders leads, such pipe being provided
 15 with branches $t' t^2$, of which branch t' is connected with the valve box of the ram n , while branch t^2 is connected with the valve box of the ram o . The valve stem u for the valve of the ram n is controlled by a hand lever or its equivalent u' suitably connected therewith, while the valve stem v for the valve of the ram o is operable by a suitable hand lever v' . In practice it is preferable to employ pilot-valves interposed between the main valves and the operating levers. x indicates the discharge pipe leading from the rams or
 20 hydraulic cylinders u' , the same discharging into the tank r , which is preferably covered.

The rope, chain or cable l may be termed the closing rope and the rope k the tripping or dumping rope, for the reason that when there is slack in the rope k the
 25 rope l , acting through the drum m , will close the parts of the carrier a , whereas, when there is slack in the rope l and the rope k is drawn taut, the parts of the carrier are opened. The ropes k and l may both be used in raising or lowering the carrier containing material, or the rope l may alone be used.

It will be observed that the trolley or carriage g in its motion to and fro does not affect the height of the bucket so that the bucket may be hoisted to a fixed point, no matter where it is, and makes it possible to
 35 stop the lifting machinery at a fixed point by any suitable automatic mechanism used for that purpose. Under this invention it is also possible to run the trolley or carriage at a greater speed than heretofore.

The trolley or carriage may be moved either by the
 40 motor geared to its wheels or rollers, as shown, or it may be hauled in and out in any other suitable manner.

In the form of the invention shown it will be seen that it comprises kinetic or dynamic means for supply-

ing pressure independently, or substantially independently, of the flow or quantity of fluid supplied, and 55 it also provides means for economically operating the apparatus by a constantly running motor. An electric motor is the one most desired, and when used the well known speed regulating properties of a shunt-wound motor contribute to the maintaining of a substantially uniform static pressure by a constantly actuated 60 kinetic or dynamic means.

The subject matter of this application forms part of the subject matter disclosed in my application filed on the fourth day of February, 1904 Serial No. 191,925 65 which application contains generic claims covering the present invention and certain specific improvements not claimable herein.

Having thus described my invention and without limiting myself to details or enumerating equivalents, 70 what I claim as new and desire to secure by Letters Patent is:

1. In combination with a clam-shell bucket or other carrier, doubled ropes or tension devices for giving it motion of translation in a vertical direction and operating 75 its parts, means for balancing the tension of the ropes or tension devices at both sides of said carrier, a trolley or carriage from which the said ropes suspend the carrier, and hydraulic cylinders and pulleys acting upon loops or bights of said ropes, for substantially the purposes set 80 forth.

2. In combination with a clam-shell bucket or other carrier, doubled ropes or tension devices for giving it motion of translation in a vertical direction and operating its parts, means for balancing the tension of the ropes or tension devices at both sides of said carrier, a trolley or carriage from which the said ropes suspend the said carrier, rams or hydraulic cylinders acting upon the loops or bights of said ropes, and independent means for actuating said trolley, for substantially the purposes set forth. 90

3. In hoisting apparatus, the combination with a self-closing bucket, of a doubled rope for imparting vertical movement to said bucket and balanced on both sides, a doubled rope for operating the parts of the bucket and also balanced on both sides, and operating devices engaging the loops of said ropes, for substantially the purposes set forth. 95

4. In hoisting apparatus, the combination with a clam-shell or other self-closing bucket, of a doubled rope having both ends attached to the bucket for hoisting the bucket, 100 pulleys for guiding the two leads of the rope in opposite directions from the bucket, a second doubled rope having its ends secured to the bucket for operating the parts of the bucket, pulleys guiding the leads or runs of the second rope in opposite directions from the bucket, sheaves engaging the bights or loops of said doubled ropes, and means for applying power to said sheaves, for substantially the purposes set forth. 105

In testimony whereof I have signed this specification in the presence of two subscribing witnesses.

LINCOLN MOSS.
